UNITED STATES PATENT OFFICE.

WARREN FISHER, OF NEW ORLEANS, LOUISIANA.

GRATE.

1,255,727.

Specification of Letters Patent.

Patented Feb. 5, 1918.

Application filed November 8, 1916. Serial No. 130,237.

To all whom it may concern:

Be it known that I, WARREN FISHER, a citizen of the United States, residing at New Orleans, in the parish of Orleans and State of Louisiana, have invented certain new and useful Improvements in Grates; and I do hereby declare the following to be a full, clear, and exact description of the invention, such as will enable others skilled in the art to which it appertains to make and use the same.

The present invention relates to improvements in grates, and more particularly to improved fire-bars, in which air or other fluid is introduced from a source of supply through passages and opening in the fire-bars in order to maintain the same at a comparatively low temperature, prolonging the life of the fire-bar by preventing the burning and warping thereof, and into the furnace where such fluid will furnish an increased draft and aid in the combustion of the fuel. It will also be seen there is abundant air space in the bars and that the bars can be used for natural draft, and still be amply strong and give high efficiency.

The improved structure is more especially designed to give good results in burning of bagasse and sawdust, or other waste fuels, although it will be found to give good results in burning wood, coal, or other fuels. However, it is especially designed for burning bagasse and the air space between the teeth is large.

One object of the present invention lies in providing the fire-bars of a substantial construction, not to any appreciable extent weakened by the fluid passages and openings, and one in which convenient access is to be had for cleaning the same of any ash or foreign matter that may have found its way into the fluid passages through the openings.

It is another object of the present invention to so arrange and dispose the lugs and openings on the several fire-bars that, when assembled to form the grate, such lugs will be received between the proximate lugs in the adjacent fire-bar, leaving spaces to either side thereof where the fluid is directed from the openings therein.

With these and other objects in view the invention consists in the novel details of construction and combinations of parts more fully hereinafter disclosed and particularly pointed out in the claims.

In the accompanying drawings forming

a part of this application, and in which similar reference symbols indicate corresponding parts in the several views:

Figure 1 is a fragmentary front view of a furnace showing the grate operating means.

Fig. 2 is a sectional view through the furnace showing assembled fire-bars composing the grate in top plan.

Fig. 3 is a sectional view taken on the line 3—3 in Fig. 2, with parts broken away.

Fig. 4 is an enlarged top plan view, partly in section, of an improved fire-bar constructed in accordance with the present invention.

Fig. 5 is a side elevational view thereof.

Fig. 6 is an end view of the improved bar, and

Fig. 7 is a cross sectional view therethrough on the line 7—7 in Fig. 4.

Referring more particularly to the drawings, 1 designates generally a furnace structure which is preferably of refractory material, incased and bound together by the outer metal covering 2, but the outer metal covering is not necessary, and is not always used.

The front of the furnace is indicated at 3, in which are the usual doors 4 leading to the grate, and through which the fuel is introduced, and the doors 5 through which access is had to the ash pit, indicated at 6 in Fig. 3.

At 7 is indicated a bar extending across the front of the furnace, and at 8 a bearing bar dividing the grate into two parts holding each a series of the improved fire-bars.

Referring now more particularly to Figs. 4 to 7, inclusive, the improved fire-bar is designated generally at 9, it being formed with a series of lugs 10 and 11, extending in opposite directions, and the lugs 10 being in staggered relation to the lugs 11, as plainly seen in Fig. 4. The ends of the lugs 10 and 11 are rounded, as appears in Figs. 6 and 7, to prevent possible burning.

The body 9 of the improved fire-bar is formed with one or more passages 12, preferably extending longitudinally as shown, and communicating with such passage 12 are a plurality of openings 13 and 14, extending in diverging directions and advantageously inclined in the manner shown in Fig. 7. These openings 13 and 14 have their outer ends disposed beneath the flanges 15 and 16 of the enlarged solid head 17 of the fire-bar, such flanges affording an effective protection for the several openings

preventing any ash or other material entering therethrough into the passage 12. It will be seen from Fig. 7 that the edges 18 and 19 of the flanges 15 and 16 are inclined in such wise that any ash released by a clinker resting on the head 17 will be directed beyond the mouths of the openings 13 and 14, and will fall free thereof into the ash pit 6 below the grate.

10 The head 17 has a shallow channel 20 extending longitudinally of the fire-bar 9 for yielding a seat for the fuel, and preventing crowding of the fuel to one part of the grate. A small amount of ash collects in 15 this channel when the bars are shaken, and prevents clinkers clinging to the bar.

The improved fire-bar is supported on hollow trunnions 21 and 22, which are in communication with the passage 12 in the 20 body 9, and are threaded as at 24 to receive plugs 23, which may be removed to give access to the trunnions and passage 12 for purposes of cleaning the same of any ashes that may have crept through the openings 25 13 and 14. One trunnion 21 of each of the improved fire-bars is elongated over the opposite trunnion 22, and in such elongated trunnions 21 are formed ports 25 adapted to register with similar ports 26 in bearings 27 30 provided to receive said elongated trunnions. The bearings 27 are cast or fitted in headers 28 and 29 built in the furnace structure 1, and placed in communication with a source of air or other fluid supply through pipes 35 30 and 31. Other means may, of course, be furnished for introducing the fluid to the headers 28 and 29, and such fluid may be admitted thereto in any other manner than shown provided it does not alter the operation of the invention. The smaller trunnions 40 22 of the fire-bars are received in bearings 22 held by the bearing bar 8, for which see Fig. 2.

Referring now to Fig. 2, it will be seen 45 that when the various fire-bars are assembled to constitute the grate, they are fitted in close relation with the lugs 10 of one bar extending midway between the proximate lugs 11 of an adjacent fire-bar, leaving 50 spaces 32 and 33 therebetween.

The fluid openings 14 in one side of each fire-bar are arranged opposite the spaces 32 so as to deliver the air up through the bed of the fuel. This will result from the inclination upward given said holes. As the 55 air issues out of the holes upwardly it will draw air from the ash pit beneath up through the grate and against the lugs 10 and 11, thus tending to keep said lugs cool, 60 this cooling effect being further assisted by the fluid passing through the passage 12. The combined air delivered from the holes and the ash pit will contribute to maintain a fire of great intensity giving off increased 65 heat.

For the purposes of shaking, the fire-bars may be connected to one or more operating devices in any way desired. Preferably the grate as shown in Fig. 2 is for purposes of shaking divided into four parts and four 70 separate operating devices are provided on the front 3 of the furnace (see Fig. 1). The arms 34 on the fire-bars 9 are connected to rods 35, 36, etc., in any desired number and arrangement, such as that indicated in Fig. 75 3, and the rods 35 and 36 are respectively connected through links 37 and 38 with levers 39 and 40, fulcrumed as indicated at 41 and 42 on the front 3 of the furnace in a 80 convenient position to be operated.

Latches 43 are provided to hold the levers in a position where the fire-bars of the grate will be held upright with the lugs 10 and 11 extending horizontally; and handles 44 85 are employed to operate the several levers.

In the operation of the invention, fuel is introduced through the doors 4 and deposited on the fire-bars 9 composing the grate. The fire is kindled and as the combustion proceeds the finer ashes will pass 90 down through the spaces 32 and 33 into the ash pit 6, being diverted from the mouths of the fluid openings 13 and 14 by the inclined edges 18 and 19 on the flanges 95 15 and 16.

Air or other suitable fluid is introduced from a source of supply through the pipes 30 and 31 to the headers 28 and 29, where such fluid will enter through the registering ports 26 and 25 and pass to the passages 100 12 in the various fire-bars 9. The air, preferably being supplied under some pressure, will seek exit through the openings 13 and 14, where it will be directed up into the furnace through spaces 32 and 33, between 105 the lugs 10 and 11, on which it will exert a cooling effect by increasing the furnace draft. The presence of fluid in the passages 12 will also have a cooling effect on the fire-bars 9 as a whole, and will keep the 110 same at a comparatively low temperature in the furnace, such as will prevent the burning and warping of the fire-bar consequent upon expansion and contraction, and will thus prolong its life. As the air or other 115 fluid employed passes through the openings 13 and 14, it will come into active contact with the burning fuel, and will rise upwardly through the burning bed, furnishing an increased draft and aiding in the 120 combustion.

The handles 44 may be applied over the proper levers 39 and 40 when the fire is to be cleaned, and the latches 43 released, whereupon, by oscillating the handles and 125 levers, the fire-bars will be similarly moved to swing their lugs 10 and 11 into the vertical position, thereby allowing the ashes to drop through the spaces therebetween. When the teeth on one bar pass between the 13

teeth on the adjacent bar they clear out all clinker and ash, and quickly clean the fire, and prevent the air spaces from clogging. By giving the bars part oscillation the bed 5 of the fuel is broken and shaken up and combustion increased.

When cleaning is desired, the fire-bars are removed and the plugs 23 are withdrawn, thus giving uninterrupted access to 10 the passages 12. After the ashes and foreign matter have been cleared from the passages 12 and openings 13 and 14, the plugs 23 may be replaced and the fire-bars again returned to the furnace.

15 Having thus described my invention, what I claim and desire to secure by Letters Patent of the United States is:

1. A one-piece cast grate-bar formed with a body having a longitudinal passage and 20 with teeth extending in opposite directions and staggered relation, the body having a staggered series of openings connecting with said passage and extending upward in divergent relation, one opening being placed 25 between each pair of teeth and very close to the face of one of such teeth, such body provided with a head having a channel lengthwise thereof and flanges projecting over the mouths of said openings, said 30 flanges having inclined edges, the body of

the grate-bar further having hollow journals with internally threaded ends, one of the journals being enlarged and having an opening through the side thereof to communicate with a fluid-supply source, and 35 threaded plugs fitting in the ends of said journals, substantially as described.

2. A grate including a series of fire bars, each of said fire bars being formed of a one-piece cast body having a longitudinal 40 passage and teeth extending in opposite directions and staggered relation, said body having a staggered series of openings connected with said passage and extending upward in divergent relation, one opening being 45 placed between each pair of teeth and very close to the face of one of such teeth, such body being provided with a head having a channel lengthwise thereof and flanges projecting over the mouths of said openings, 50 said flanges having inclined edges, the body of the fire bar further having hollow journals with internally threaded ends, one of the journals being enlarged and having an opening through the side thereof to communicate with a fluid supply source, and 55 threaded plugs fitting in the ends of said journals, substantially as described.

In testimony whereof, I affix my signature.
WARREN FISHER.
